UNITED STATES PATENT OFFICE.

LOUIS GOHLKE, OF GRAND RAPIDS, MICHIGAN.

DESIGN FOR A BAIL FOR CARPET-SWEEPERS.

SPECIFICATION forming part of Design No. 24,009, dated February 5, 1895.

Application filed January 5, 1895. Serial No. 533,974. Term of patent 7 years.

To all whom it may concern:

Be it known that I, LOUIS GOHLKE, a citizen of the United States, residing at Grand Rapids, in the county of Kent and State of Michigan, have invented a certain new and useful Design for Bails; and I do hereby declare the following to be a full, clear, and exact description of the invention, such as will enable others skilled in the art to which it appertains to make and use the same.

This design relates to a bail for carpet sweepers, or other analogous structures and the distinctive features thereof are the oppositely extended and curved arms, having curved ornamentation, in conjunction with a central handle socket, as more fully illustrated in the accompanying drawings, in which—

Figure 1 is a side elevation of a carpet sweeper bail embodying said design; Fig. 2, a

plan view of the same, and Fig. 3 an end elevation of the same.

Like letters refer to like parts in all of the figures.

A represents a central cylindrical socket; B, B, oppositely extended downwardly curved and carved arms; C, C, oppositely extended and oppositely curved, carved extensions of the same; and D, D, parallel depending arms having rope molded surfaces.

What I claim is—

The design for a bail substantially as herein shown and described.

In testimony whereof I affix my signature in presence of two witnesses.

LOUIS GOHLKE.

Witnesses:

LUTHER V. MOULTON,
LOIS MOULTON.
